UNITED STATES PATENT OFFICE.

RICHARD SMITH, OF PHILADELPHIA, PENNSYLVANIA, ASSIGNOR TO
MACKELLAR, SMITHS & JORDAN, OF SAME PLACE.

DESIGN FOR PRINTING-TYPES.

Specification forming part of Design No. **6,892**, dated September 23, 1873; application filed September 1, 1873.
[Term of Patent 7 years.]

To all whom it may concern:

Be it known that I, RICHARD SMITH, assignor to MACKELLAR, SMITHS & JORDAN, of the city and county of Philadelphia, Pennsylvania, have originated and produced a new and original Design for Printing-Type, of which the following is a specification:

The nature of my design for printing-type is clearly shown in the accompanying typ-

graphic impressions, to which reference is made.

What I claim as new is—

The design for printing-type, as shown.

RICHARD SMITH.

In presence of—

C. F. HUCH,
JAS. G. BERKHEIMER.
